UNITED STATES PATENT OFFICE.

PAUL SIBLEY, OF WORCESTER, MASSACHUSETTS.

MULTIPOLEAR SWITCH.

1,417,576.

Specification of Letters Patent. Patented May 30, 1922.

Application filed March 26, 1921. Serial No. 455,307.

To all whom it may concern:

Be it known that I, PAUL SIBLEY, a citizen of the United States, residing at Worcester, in the county of Worcester and State of 5 Massachusetts, have invented a new and useful Multipolar Switch, of which the following is a specification.

The object of this invention is to provide a new and improved multi-polar switch by 10 which many permutations or combinations of various circuits can easily be obtained.

The switch has been especially designed for use in connection with a transformer, although the same is capable of other uses.

15 The invention is illustrated in the accompanying two sheets of drawings forming part of this application, in which—

Fig. 1 is a diagram illustrating how two of my switches may be used in connection 20 with a transformer;

Fig. 2 is a plan view of the switch with the cover removed;

Fig. 3 is a cross sectional elevation taken on the line 3—3 of Fig. 2; and

25 Figs. 4 to 13 inclusive are diagrams illustrating the different ways the switch may be set.

The invention will be best understood by first giving a detail description of the switch, 30 and to follow this description reference should be had to Figs. 2 and 3 of the drawings.

Referring to the same and in detail, A designates the switch body or casing which 35 is preferably made in cylindrical shape with a bottom plate B.

C designates a circular rib or partition which is secured in the body so as to divide the same into an outer annular chamber D, 40 and an inner circular chamber E. F designates a cover which may be secured to the body by any desired means.

A shaft G is socketed in the bottom B and has a wing G' secured to which is a bottom 45 distributor bar H made of conducting material, such as copper, the shaft G preferably being made of insulating material.

A bushing I is fitted on the shaft G, and the same is provided with a wing I', secured 50 to which is an upper distributor bar J preferably made of copper, the hub I being made of insulating material.

A knob or handle K is secured on the shaft G and a knob or handle L is secured 55 on the bushing I, these knobs or handles being provided for setting the switch.

A three armed frame or segment N is carried by the distributor bar H, preferably by pivoting the same thereto and by holding the same in position relatively to the 60 bar H by a spring O which is arranged to pull the frame against a stop O'. The frame N is preferably made of insulating material, and carries three connecting pieces N, N' and N² preferably made of copper. 65

10 designates the binding post for the leading-in wire, and 11 the binding post for the leading-out wire.

Contacts 12, 13, 14 and 15 are secured to the partition C in position so that one end 70 of the distributor bar H will cooperate with the surfaces thereof next the bottom B. The contact 12 is connected to the post 10, and the contacts 12, 13, 14 and 15 are connected together by a bus-bar 16 arranged on 75 the bottom of the switch.

Contacts 17, 18, 19 and 20 are also secured to the partition C so that their surfaces next the cover F will come in a plane to co-operate with one end of the distributor 80 bar J. The post 11 is connected to a bus-bar 21 and the contacts 17, 18, 19 and 20 are connected to said bus-bar.

Contacts 22, 23, 24 and 25 are connected to or carried by the partition C on the opposite side of the switch relatively to the contacts previously described, these contacts having their surfaces next the bottom B of the switch set in a plane so that the other end of the distributor bar H can co- 85 operate therewith. 90

Another set of contacts 26, 27 28 and 29 is also carried by this part of the partition C, the upper faces thereof being set in a plane so that the other end of the distributor 95 bar J can co-operate therewith.

The contact 17 is provided with a stop 170 and the contact 20 is provided with a stop 200 to limit the motion of the distributor bar J, and the contact 22 is provided with 100 a stop 220 and the contact 25 with a stop 250 to limit the motion of the distributor bar H.

The contacts 26 and 23 form a pair of contacts or in other words they are arranged 105 relatively to each other so that when the connecting piece N is in the position shown in Fig. 2 they will be electrically connected together. The contacts 28 and 25 also form a pair of contacts arranged so that when 110 the connecting piece N² is in the position shown in Fig. 2 they will be connected

together. The contacts 27 and 24 also will be connected together when the connecting piece N occupies the position at which the connecting piece N' is shown in Fig. 2, 5 and the contacts 28 and 25 will also be connected together when the connecting piece N' occupies the position which N² occupies in Fig. 2.

The contacts 12, 13, 14 and 15, and 17, 18, 10 19 and 20 are set at a slightly greater distance from the center so that the contact pieces N, N' and N² will not co-operate therewith.

The contacts 22 and 26 are connected to a 15 circuit 1; the contacts 23 and 27 to a circuit 2; the contacts 24 and 28 to a circuit 4; and the contacts 25 and 29 to a circuit 8, as illustrated in Fig. 1.

In the specific application shown of my 20 switch, circuit 1 includes a primary winding P' on a transformer T; circuit 2 includes a winding P² on the transformer; circuit 4 includes a winding P⁴ on the transformer; and circuit 8 includes a winding P⁸ 25 on the transformer. These windings may be arranged in the ratio in which they are above specified; that is, relatively as 1, 2, 4 and 8.

This is a convenient arrangement for getting 30 a number of permutations for connecting the coils in series. These permutations can be easily followed by referring to the second sheet of drawings, and by considering the distributor bar H as controlling the 35 inflow of the current, and the bar J the outflow of the current.

Thus in Fig. 4 coil 1 is connected; in Fig. 5 coil 2 is connected; in Fig. 6 coils 1 and 2 are connected, the connecting piece N joining 40 them in series; in Fig. 7 coil 4 is connected; in Fig. 8, coils 2 and 4 are connected, connecting piece N connecting these coils in series; in Fig. 9 coils 1, 2 and 4 are connected, connecting pieces N and N' connecting 45 these coils in series; in Fig. 10 coil 8 is connected; in Fig. 11 coils 4 and 8 are connected, connecting piece N connecting these coils in series; in Fig. 12 coils 2, 4 and 8 are connected, the connecting pieces N and 50 N' connecting these coils in series; and in Fig. 13 coils 1, 2, 4 and 8 are connected, connecting pieces N, N' and N² connecting these coils in series.

Thus with the coils arranged in the ratio previously described, the windings of the 55 transformer may be connected in any one of the multiples 1, 2, 3, 4, 6, 7, 8, 12, 14 and 15.

This forms a desirable switch for changing the voltage of the primary winding of 60 a transformer. If high voltages are to be handled the switch can be filled with oil.

If desired the secondary winding of the transformer may be arranged in a similar way, that is, may be divided into coils S', 65 S², S⁴ and S⁸, and these may be connected and controlled by another one of my switches as will be readily understood by referring to Fig. 1 of the drawings.

By using two switches in this way a great 70 many different voltages can be obtained. My switch may be applied for other uses.

The details and arrangements herein shown and described may be greatly varied by a skilled electrician without departing 75 from the scope of my invention as expressed in the claims.

Having thus fully described my invention what I claim and desire to secure by Letters-patent is:—

1. An electric switch having two series of contacts arranged in pairs, two distributor bars co-operating therewith, and a contact piece carried by one of the distributor bars for connecting the contacts of each pair. 80

2. An electric switch consisting of a series of contacts arranged in pairs, a distributor bar for co-operating with one set of contacts of the pairs, another distributor-bar co-operating with the other set of contacts 90 of the pairs, and a plurality of connecting pieces carried by one of the distributor bars for connecting the contacts making up the pairs.

3. An electrical switch comprising two 95 series of contacts arranged in different planes, a distributor bar coacting with the contacts arranged in one plane, a distributor bar co-acting with the contacts arranged in the other plane, and a plurality of connecting pieces carried by one of the distributor bars for connecting the contacts making up the pairs together.

In testimony whereof I have hereunto affixed my signature.

PAUL SIBLEY.
